(57) **CLAIM**

The ornamental design for a hand-operated circular saw, as shown and described.

DESCRIPTION

FIG. 1 is a perspective view of the front-left side of the hand-operated circular saw showing the present design;

FIG. 2 is a perspective view of the rear-left side of the hand-operated circular saw of FIG. 1;

FIG. 3 is a plan view of the left side of the hand-operated circular saw of FIG. 1;

FIG. 4 is a plan view of the right side of the hand-operated circular saw of FIG. 1;

FIG. 5 is a plan view of the top side of the hand-operated circular saw of FIG. 1;

FIG. 6 is a plan view of the front side of the hand-operated circular saw of FIG. 1; and,

FIG. 7 is a plan view of the rear side of the hand-operated circular saw of FIG. 1.
